The ornamental design for a ball chair frame, as shown and described.

DESCRIPTION

FIG. 1 is a perspective view of a ball chair frame as seen from above according to our new design.

FIG. 2 is a perspective view thereof as seen from below.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof; and,

FIG. 9 is a perspective view analogous to FIG. 1, and showing a ball on the ball chair frame in dashed lines during use.

The dashed lines throughout the drawings show environmental structure that form no part of the claimed design.
